Wittelboehm

UNITED STATES PATENT OFFICE.

WILHELM BOEHM, OF BERLIN, GERMANY.

FREE-BURNING CANDLE.

Application filed March 23, 1922. Serial No. 546,206.

To all whom it may concern:

Be it known that I, WILHELM BOEHM, a subject of Prussia, residing at Berlin, Germany, have invented certain new and useful 5 Improvements in a Free-Burning Candle, of which the following is a specification.

My invention relates to a free burning candle of the kind in which an illuminating material such, for instance as metallic magnesium is used as a source of light. It is 10 the object of my invention to produce such a free burning candle which is complete in itself and always ready for use. For that purpose I enwrap a part of a holding rod 15 of non-combustible material such as iron or the like, with a foil of metallic magnesium so tightly that said foil gets hold on said rod without the assistance of any other means. To prevent any accidental sliding 20 of said foil relatively to said holding rod I provide the enwrapped part of said holder with a curvature or any other structural departure from the straight line of the main part of the holder. To facilitate the ignition 25 of the wrapping foil I provide at one end of said foil at least one incision whereby tongues of magnesium foil are produced which are apt to readily catch fire.

A free burning candle according to my 30 present invention is illustrated, by way of example, in the accompanying drawing, in which Figure 1 represents in elevation, a side view, and Figure 2 a front view of my new article. Figure 3 is a plan view of 35 Figure 1.

The holder of non-combustible material is designated by the reference numeral 1, and is partly enwrapped by a foil 2 of metallic magnesium, the upper end of which foil is 40 provided with an incision 4, whereby two small tongues 5, 6, are produced which will readily catch fire when being ignited. Towards the lower end I provide a curvature 3 which prevents any relative sliding movement between holder 1 and wrapper 2.

The free burning candle according to my present invention may be used for making

snapshot photos, and will also be appreciated as a children's toy. Since the burning magnesium is prevented from detaching itself 50 from the holder there is no danger of spreading fire involved in burning such a toy candle.

What I claim is:

1. A free burning candle, comprising in 55 combination, a rod of non-combustible material, and a foil of metallic magnesium, said foil enwrapping said rod so tightly as to be held in position on said rod.

2. A free burning candle, comprising in 60 combination, a rod of non-combustible material, a foil of metallic magnesium, said foil enwrapping said rod so tightly as to be held in position on said rod, and at least one incision at one end of said foil, whereby the 65 ignition of said foil is facilitated.

3. A free burning candle comprising in 70 combination, a rod of non-combustible material, a foil of metallic magnesium, said foil enwrapping said rod so tightly as to be held in position on said rod, and a curvature within the enwrapped part of said rod and comprising both said rod and said foil enwrapping said rod, whereby said foil is secured against any accidental sliding relatively to said rod.

4. A free burning candle comprising in 75 combination, a rod of non-combustible material, a foil of metallic magnesium, said foil enwrapping said rod so tightly as to be held in position on said rod, and at least one incision at one end of said foil, whereby the 80 ignition of said foil is facilitated, and a curvature within the enwrapped part on said rod and comprising both said rod and said foil enwrapping said rod, whereby said foil is secured against any accidental sliding relatively to said rod.

In testimony whereof I affix my signature in presence of two witnesses.

WILHELM BOEHM.
